JOSEPH C. HIGGINS AND THOMAS LEA, OF NEW BRUNSWICK, NEW JERSEY,
ASSIGNORS OF ONE-TWENTIETH TO A. VAN NEST BALDWIN, OF SAME
PLACE.

EXPANSIBLE HORSESHOE-CALK.

SPECIFICATION forming part of Letters Patent No. 477,542, dated June 21, 1892.

Application filed November 13, 1891. Serial No. 411,797. (No model.) Patented in France December 8, 1891, No. 217,927, and in Belgium December 31, 1891, No. 97,490.

To all whom it may concern:

Be it known that we, JOSEPH C. HIGGINS and THOMAS LEA, of New Brunswick, in the county of Middlesex and State of New Jersey, have invented certain new and useful Improvements in Horseshoe-Calks, (for which 5 patents have been obtained in France, dated December 8, 1891, No. 217,927, and in Belgium, dated December 31, 1891, No. 97,490, and for which applications have been filed in Canada, No. 58,424, dated November 16, 1891; in England, No. 21,415, dated December 8, 1891, and in Germany, No. 11,744, dated December 8, 1891;) and we do hereby declare 15 that the following is a full, clear, and exact description of the invention, which will enable others skilled in the art to which it appertains to make and use the same, reference being had to the accompanying drawings, and 20 to the letters of reference marked thereon, which form part of this specification.

This invention relates to certain improvements in horseshoe-calks.

The object of the invention is to provide an 25 improved horseshoe-calk exceedingly simple, cheap, and durable in construction and composed of a minimum number of parts, the primary object being great strength and ease and sureness of attachment, whereby when 30 the calk is once secured it will not become loose, but continued concussion will the more firmly lock it in place in the shoe.

This invention consists in certain novel features of construction and in combinations of 35 parts more fully described hereinafter, and particularly pointed out in the claims.

Referring to the accompanying drawings, Figure 1 is a section of the horseshoe, showing our improved calk secured in position 40 therein. Fig. 2 is a view showing the calk and its expanding-pin in elevation. Fig. 3 is an end view of the calk. Figs. 4 and 5 are respectively end views of the shanks of two calks having a different number of slits or 45 cuts. Figs. 6 and 7 show different forms of expanding-pins. Fig. 8 is a detail view of a tool for removing the calks, shown on a reduced scale.

In the drawings, *a* indicates a horseshoe. 50 In carrying out our invention we provide

the shoe with apertures *b*, each of a size to snugly receive a shank of the calk. We usually place two calks at the toe of the shoe and a calk at each heel; but of course the calks can be arranged as desired. Each calk 55 consists of the outer contact ends *c*, of any suitable and desirable shape, preferably conical, as shown, although we do not limit ourselves to this particular shape, and the shank *d*, of a shape to snugly fit the shoe-aperture. 60 The shoulder *e* is preferably formed at the base of the shank to bear against the under surface of the shoe. The shank can be of any desired shape, although we prefer to have it cylindrical, as shown. Each calk is prefer- 65 ably formed integral and in one piece of suitable hard metal. The shank of the calk is made expansible, preferably, by one or more slits or cuts *f*, extending longitudinally through the shank, preferably, a suitable dis- 70 tance into the outer portion of the calk. The shank can be formed expansible by any de- 75 sired number of slits or cuts from one up. Preferably two slits in planes at right angles to each other are employed, as shown in Fig. 75 5. These slits form the shanks of tongues, which are forced out. The calk is provided with a central longitudinal passage, prefer- 80 ably extending from its contact end com- 85 pletely throughout its length, to receive the pin *g*, and the shape of the expanding-pin and interior of this opening are so relatively arranged that when the pin is forced in toward the rear or shank end of the calk it forces the sides of the calk under great pressure against 85 the sides of the shoe-opening. The expand- 90 ing-pin is preferably tapered and the portion of the longitudinal opening within the shank is preferably contracted, so that the pin passes freely through the outer portion of the open- 95 ing, but engages the slits of the openings within the shank and forces the sides of the shank out when the pin is forced in. The expanding-pin extends from the contact end of the calk inwardly. Hence all concussions 95 caused by the calk striking the ground or pavement when in use constantly forces the pin up and maintains the shank constantly expanded within the shoe-aperture.

In securing the calks the shank of each calk 100

is inserted in its shoe-aperture, and then the expanding-pin is inserted in the calk from the point thereof and driven in until the shank is firmly and rigidly locked in the shoe, and the greater and heavier the concussions on the point of the calk the more rigidly and firmly it is locked in the shoe. The expanding-pin extends longitudinally within the calk, so that it is free to be driven up-
wardly independently of the shoe as the parts wear or loosen, thereby maintaining the calk constantly locked strongly and rigidly. The expanding-pin can be of any desired shape, such as round, flat, or angular in cross-section, as shown in the drawings.

k indicates a tool for removing the calks from the shoe without removing the shoe from the hoof. This tool has a beveled edge to be driven between the shoulder of the calks and face of the shoe, and thereby force or prize out the calk. The beveled or wedge-shaped end has a notch or recess, as shown, to fit the shank of the calks.

Having fully described our invention, what we claim as new, and desire to secure by Letters Patent of the United States, is—

1. The calk in one piece, having its shank

split and expansible, the longitudinal passage through the calk, and the expanding-pin in such passage, combined and arranged to operate as set forth.

2. The calk in one piece, with its shank split longitudinally to render it expansible and having the passage extending longitudinally through the calk and contracted within the shank, and the expanding-pin, combined to operate as set forth.

3. The herein-described horseshoe-calk, having the expansible shank, and the expanding-pin extending from the contact end of the calk longitudinally within the same, said pin being inclosed within the calk, the pin and the portion of the pin-passage within the shank being so relatively formed by a bulge as to expand the shank as the pin is forced inwardly, substantially as described.

In testimony that we claim the foregoing as our own we affix our signatures in presence of two witnesses.

JOSEPH C. HIGGINS.
THOMAS LEA.
